UNITED STATES PATENT OFFICE.

GEORGE M. HUBINGER, OF MILWAUKEE, WISCONSIN, ASSIGNOR TO STAR DETACHABLE TOWEL HOLDER CO., OF MILWAUKEE, WISCONSIN.

TOWEL CABINET.

Application filed June 9, 1926. Serial No. 114,687.

This invention relates to a towel dispensing device.

In devices, as heretofore constructed, it has been the usual custom to provide either a cabinet for the reception of the towels, with means for retaining the towels temporarily in place upon a supporting rod, or else to provide means adjacent the outer end of the rod for impeding the removal of towels therefrom.

These constructions are necessarily complicated, and require material and somewhat difficult manipulation of the towels to remove them from the rod, and also require specially formed terminal portions for the rod or else additional apparatus associated therewith.

This invention overcomes the defects noted above, and objects of such invention are to provide a novel form of towel dispensing device in which the rod is looped to provide not only an extensive and compact support for the towels so that a large number may be carried in a small space, but also to provide a novel form of supporting rod so shaped as to cause the towels carried thereby to interengage and thus of themselves impede the outward progress or removal of the outermost towel from the rod.

This eliminates the necessity of either impeding means carried by the rod, or additional means supported adjacent the end of the rod. Instead of these complicated constructions, the rod is so looped that the towels form the impeding means to prevent wholesale removal of the towels, either intentionally or inadvertently from the rod, and yet permit a single towel to be removed therefrom in regular succession.

Further objects are to provide a cheaper, simpler, and more reliable construction than has heretofore been possible.

Embodiments of the invention are shown in the accompanying drawings in which:

Figure 1 is a side elevation of the device with parts broken away;

Figure 2 is a plan view of the structure shown in Figure 1, showing diagrammatically a view of the towels in position;

Figure 3 is a sectional view on the line 3-3 of Figure 1;

Figure 4 is a perspective view of a modified form of rod;

Figure 5 is a face view of one of the locking discs or members.

Figures 1 to 3 will first be described. In

this form of the invention, it will be seen that a bracket 1 is provided which is preferably formed of sheet metal with outwardly projecting apertured flanges, so that it may be attached to a support, such as indicated at 2. This sheet metal member is provided with a forwardly projecting web 3 formed of the two plates of the member and riveted together, as indicated in Figures 1 and 3. Between these webs a circular aperture or channel 4 is provided for the reception of the end of the rod 5. Further, the web is provided with a vertical channel for the reception of a locking pin or other device 6. This locking pin is adapted to fit within a hole or recessed portion of the rod 5, as indicated in Figure 70. Further, as shown in Figures 1 and 3, a key in the form of a small plate 7 is held between the outwardly projecting webs and enters a keyway 8 formed in the rod, as shown in Figure 1. The rod is also provided with a locking disc 9 of any suitable type, such locking disc being adapted to engage a recess or groove formed in the rod, as indicated by the reference character 10 in Figure 4. This locking disc may be operated by means of a key in any suitable manner.

The rod 5 is thus rigidly held against motion of translation and against rotation by means of the bracket 1. This rod is provided with a looped or curved portion, such as indicated at 11 in Figure 2, so that it is looped back of itself and provided with a free end adjacent the outermost portion of the rod. This free end carries a chain or other receiving member 12. This chain is adapted to receive the soiled towels and terminates in a plug or member 13, which may carry one of the locking discs 9.

In using this device, the towels are slipped onto the rod either from its straight end or along the chain, and from thence onto the rod. It is preferable, however, to slip the towels onto the rod from the straight end, as this may be more conveniently done. The towels are positioned upon the circular or looped portion 11, and it is to be noted that the towels will interengage, that is to say, their inwardly directed edges will interlock and prevent the wholesale inadvertent removal of a number of towels from the rod. However, a single towel may be readily removed from the rod and slid downwardly upon the chain 12, after it has been used.

It is to be particularly noted that the towels themselves restrain the free outwardly sliding of the outermost towel by the interengagement of their inner edges.

5 The same inventive idea is embodied in the form illustrated in Figure 4 from which it will be seen that the looped portion 14 is in the form of rectangle instead of a circle. Preferably, this rectangle is joined to the 10 body of the rod by means of a downwardly extending portion 15, although this portion may be dispensed with, provided the looped structure is retained. The usual chain and 15 terminal locking member, therefore, is employed with this form of rod, as described above.

It is to be particularly noted that this construction permits a very simple formation of the rod, and requires no auxiliary apparatus 20 to restrain the outward motion of the towels, nor does it require any special formation of the terminal or outer end of the rod. Instead, the towels are relied upon and have been found in actual practice to afford the 25 requisite impedance against outward motion of the outermost towel.

It is to be noted further that the construction is extremely simple and may be very 30 cheaply produced. Further, it is to be noted that the looped portion provides an extensive support for the towels and permits the placing of a large number of towels in a very small or compact space.

Although the invention has been described 35 in considerable detail, such description is intended as illustrative rather than limiting as the invention may be variously embodied and as the scope of such invention is to be determined as claimed.

I claim:

1. A towel dispensing device, comprising a bracket adapted for attachment to a support, a rod carried thereby and coiled upon itself to provide an extensive towel retaining portion, said coiled and storing portion causing 45 the towels to interengage in the interior of the coiled portion and impede the progress of the towels from the looped portion.

2. A towel dispensing member, comprising a bracket adapted for attachment to a support, a rod removably locked therein against motion of translation or motion of rotation, said rod having a coiled portion adapted to retain a supply of towels, said coiled portion causing interengagement of the towels in the 50 interior of the coiled portion to impede the outward progress of the outermost towel, said rod having a free outer end provided with a downwardly extending member.

3. A towel dispensing member comprising 55 a bracket adapted for attachment to a support, a rod removably locked therein against motion of translation or motion of rotation, said rod having a coiled portion adapted to retain a supply of towels, said coiled portion causing interengagement of the towels in the interior of the coiled portion to impede the outward progress of the outermost towel, said rod having an outer end provided with a 60 downwardly extending member, the outer end of said member having means for preventing the unauthorized removal of towels therefrom.

In testimony that I claim the foregoing I have hereunto set my hand at Milwaukee, in 75 the county of Milwaukee and State of Wisconsin.

GEORGE M. HUBINGER.
